(57) **CLAIM**

The ornamental design for a power connector, as shown and described.

DESCRIPTION

FIG. 1 is a top, front, right side perspective view for a power connector, showing our new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

In FIG. 3, the broken lines are for the purpose of illustrating portions of the power connector that form no part of the claimed design.
